UNITED STATES PATENT OFFICE.

ELMER E. HAUER, OF SPRINGFIELD, OHIO, ASSIGNEE TO THE LAGONDA MANUFACTURING COMPANY, OF SPRINGFIELD, OHIO, A CORPORATION OF OHIO.

ROTARY MOTOR.

1,124,614.

Specification of Letters Patent. Patented Jan. 12, 1915.

Application filed August 8, 1914. Serial No. 354,764.

To all whom it may concern:

Be it known that I, ELMER E. HAUER, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors and more particularly to a rotary motor for driving tube cleaners that is adapted to travel through a tube with the cleaner, although it may be used for other purposes.

15 The object of my invention is to provide an improved motor simple, strong and efficient to meet the severe duty of the special purpose for which it is particularly designed.

20 A further object is to provide improved means for attaching the tool to be driven and securing the rotary motor member to its shaft.

A further object is to provide improved 25 bearings adapted to both carry and take the end thrust of the rotary motor member.

With these and other objects in view my invention consists of the constructions and combinations hereinafter described and set 30 forth in the claims.

In the accompanying drawings which form a part of this specification Figure 1 is a longitudinal section of a motor embodying my invention; Fig. 2 is a front end view; 35 Figs. 3 and 4 are cross-sections on the lines 3—3 and 4—4 respectively of Fig. 1; Fig. 5 is a longitudinal section showing a modification of the motor; Figs. 6 and 7 are cross-sections on the lines 6—6 and 7—7 of Fig. 40 5; Fig. 8 is a longitudinal section showing another form of bearings and Figs. 9 and 10 are cross-sections on the lines 9—9 and 10—10 respectively of Fig. 8.

Like numerals represent the same parts in 45 the several views.

In the drawings a body or casing having a supply head 1 and forwardly projecting cylinders 2 and 3 with a cross-partition 4 within the inner cylinder 3 is preferably 50 formed integrally as shown. The inlet 5 of the supply head opens into the inner cylinder 3 and an opening 6 through the longitudinal wall of said cylinder admits the

motive agent to an annular chamber 7 formed between the cylinders 2 and 3. The inner cylinder 3 is shorter than the outer cylinder 2 and the bore of that portion of the outer cylinder which extends beyond the inner cylinder is enlarged forming a shoulder or inclined off-set 8. A ported partition 9 may 60 be secured in any suitable way to form the front wall of the annular chamber 7 but is shown as having inclined outer walls seated against the off-set 8 and tightened in place by being screw-threaded at 10 to the inner 65 cylinder.

A rotary motor member 11 which is shown in the form of a turbine having buckets 12 operates within the motor chamber 13 formed by the enlarged forward portion of the outer cylinder 2 in front of the ported partition. Said rotary motor member has a forwardly projecting extension 14 with a recess 15 therein extending from its front end to within the body of said member; and 70 said member is keyed to a shaft 16 by a key 17 and is tightened and held against a shoulder 18 by a nut or holding member 19 on a screw-threaded end 20 of said shaft. The recess 15 of the extension 14 is a screw-threaded for the attachment of the tool to be driven; and the outer face of said extension is formed for the engagement of a wrench as particularly shown in Fig. 2 to hold the rotary motor member while the tool 75 to be driven is secured in place.

The inner cylinder forms a bearing chamber in which the shaft is journaled, a removable bushing 21 being preferably provided which may be secured in any suitable way 80 but is shown as screw-threaded at 22 to the inner cylinder, cross-slots 23 in its forward face being provided for the engagement of a tool to secure it in place. A flange 24 on the rear end of the shaft extends between 85 the rear end of the bushing 21 and the cross-partition 4. An inlet passage 25 through the cross-partition in line with a longitudinal passage 26 in the shaft admits the motive agent to the bearings through cross-ports or passages 27 for lubrication and a chamber 28 formed between the shaft and bushing aids in the distribution. The supply head is screw-threaded at 29 for the attachment of a conduit to supply the motive 100 agent.

In Figs. 5, 6 and 7 a modified form of the motor is shown in which anti-friction bearings are employed. The shaft 16^a has an intermediate screw-threaded section 30 on opposite sides of which cones 31 are mounted, the rear cylindrical section of the shaft being smaller than the front cylindrical section to admit of assembling the parts. Sleeves or bushings 32 are seated within the bearing chamber formed by the inner cylinder 3^a. Rings 33 have oppositely disposed circular recesses 34 in which the respective ends of tapered rollers 35 are seated and arranged so that said rollers will extend beyond the inner and outer surfaces of the walls of said rings and ride upon the inclined outer surface of the cones 31 and upon the inner inclined surfaces of the sleeves or bushings 32; and said rings are held in place by pins 36 tightened in openings in the respective rings so that when the rollers are in place they will be held in assembled position. A ported partition 37 having inclined outer walls seated against an off-set 8^a of the outer cylinder 2^a is provided with a rearward extension 38 screw-threaded to the inner cylinder to tighten and hold it in place. Said partition forms the front wall of the annular chamber 7^a and closes the front end of the bearing chamber, a packing 39 being preferably employed to prevent leakage. The rear end of the sleeve 32 of the rear bearing is seated against a shoulder of the inner cylinder 3^a and the front end of the sleeve 32 of the front bearing is engaged by the ported partition and the spacing cylinder 40 is provided between the inner ends of said sleeves. Nuts 41 with lock-nuts 42 on the screw-threaded portion of the shaft are provided to adjust and hold the bearings in place. Lubricant is supplied to the bearing chamber through a passage 43 in the shaft and a plug 44 is provided to close the inlet of said passage.

Figs. 8, 9 and 10 show another form of anti-friction bearing which will now be described. A front bearing comprises a cone 45 having two race-ways, balls 46 in each of said race-ways; two separate cup-rings 47 and 48, a separator in two solid halves 49 and 50 interposed between the balls and a shell 51 is spun over the cups permanently fixing the relationship of the cone, balls and cups in a self-contained ball bearing that is adapted to both carry and take the end thrust of the shaft in both directions.

The rear bearing comprises a cone 52 having a race-way, balls 53 in said race-way, a cup-ring 54 and a split separator 55 held together by pins 56 is interposed between and carries the balls, the same being arranged as shown to both carry and take the end thrust of the shaft in one direction. These bearings are shown as being adjusted

and held in place in like manner as the bearings of Figs. 5, 6 and 7 and it is not thought necessary to repeat the description.

Having thus described my invention I claim:

1. In a rotary motor, a casing or body having a central bore and fluid supply openings for the motive agent, a shaft journaled within said bore, said shaft having a shoulder near its front end, a rotary motor member on said shaft in front of said openings and having a recess in its forward portion and a holding member within said recess on a screw-threaded end of said shaft to tighten and hold said rotary motor member against said shoulder, substantially as described. 70

2. In a rotary motor, a casing or body having a central bore and fluid supply openings for the motive agent, a shaft journaled within said bore, said shaft having a shoulder near its front end, a rotary motor member keyed to said shaft in front of said openings and having a recess in its forward portion and a holding member within said recess on a screw-threaded end of said shaft to tighten and hold said rotary motor member against said shoulder, substantially as described. 75

3. In a rotary motor, a casing or body having a central bore closed at its rear end and fluid supply openings for the motive agent, a shaft journaled within said bore, said shaft having a shoulder near its front end, a rotary motor member on said shaft in front of said openings and having a forwardly extending projection, said projection having a screw-threaded recess for the attachment of a tool, substantially as described. 80

4. In a rotary motor, a casing or body having a central bore and fluid supply openings, a shaft journaled within said bore, said shaft having a shoulder near its front end, a rotary motor member on said shaft in front of said openings and having a forwardly extending projection, said member and projection having an opening or recess extending from the front end of said projection and screw-threaded for the attachment of a tool and a holding member within said recess screw-threaded to an end of said shaft to tighten and hold said rotary motor member against said shoulder, substantially as described. 105

5. In a rotary motor, a casing or body having a central bore closed at its rear end and fluid supply openings for the motive agent, a shaft journaled in said bore, said shaft having a shoulder near its front end, a rotary motor member on said shaft in front of said shoulder with means to tighten it against said shoulder, said member having a forwardly extending projection with a screw-threaded recess therein for the attachment of a tool, the exterior of said pro- 110

115

- junction being adapted for the engagement of means to hold said member stationary while the tool is being secured in place, substantially as described.
5. 6. In a rotary motor, a supply head having two forwardly projecting cylinders, one disposed within the other forming an annular chamber between said cylinders, the longitudinal walls of the inner cylinder having an opening therethrough to admit the motive agent to said annular chamber, means introduced through the front end of said outer cylinder and secured in place to form a front ported wall for said annular chamber and close the front end of said inner cylinder and a rotary motor member in front of said ported wall having a shaft projecting through an opening in said wall and journaled within said inner cylinder, substantially as described.
10. 7. In a rotary motor, a supply head having two forwardly projecting cylinders, one disposed within the other forming an annular chamber between said cylinders, the longitudinal wall of the inner cylinder having an opening therethrough to admit the motive agent to said annular chamber, a cross-partition in front of said opening, means introduced through the front end of said outer cylinder and secured in place to form a front ported wall for said annular chamber and close the front end of said inner cylinder, a rotary motor member in front of said ported wall and having a shaft projecting through an opening in said wall and journaled within said inner cylinder in front of said cross-partition and means to take the thrust of said member, substantially as described.
15. 8. In a rotary motor, a casing or body open at its front end and having a central rearwardly extending bearing chamber closed at its rear end, an anti-friction bearing within said chamber, means introduced through said front end and secured in place to form a ported partition and close the front end of said chamber, a rotary motor member in front of said partition having a shaft projecting rearwardly through an opening in said partition and journaled in said bearing, said bearing being arranged to both carry and take the end thrust of said shaft and means to conduct the motive agent to said ported partition, substantially as described.
20. 9. In a rotary motor, a casing or body open at its front end and having a central rearwardly extending bearing chamber closed at its rear end, oppositely disposed anti-friction bearings within said chamber, means introduced through said front end and secured in place to form a ported partition and close the front end of said chamber, a rotary motor member in front of said partition having a shaft projecting rearwardly through an opening in said partition and journaled in said bearings, said bearings being arranged to both carry and take the end thrust of said shaft and means to conduct the motive agent to said ported partition, substantially as described.
25. 10. In a rotary motor, a rotary motor member having a shaft, said shaft having an intermediate screw-threaded portion, anti-friction bearings on opposite sides of said portion and means mounted on said screw-threaded portion to adjust and hold said bearings in place, substantially as described.
30. 11. In a rotary motor, a rotary motor member having a shaft, said shaft having an intermediate screw-threaded portion, anti-friction bearings on opposite sides of said portion and means mounted on said screw-threaded portion to adjust and hold said bearings in place, the shaft on one side of said portion being of less diameter than the other, substantially as described.
35. 12. In a rotary motor, a rotary motor member having a shaft and a bearing for said shaft comprising a double row of balls with a housing therefor arranged to both carry and take the end thrust of the shaft in opposite directions, substantially as described.
40. 13. In a rotary motor, a rotary motor member having a shaft and oppositely disposed anti-friction bearings therefor, one of said bearings having a double row of balls with a housing therefor arranged to both carry and take the end thrust in opposite directions, substantially as described.
45. In testimony whereof I have hereunto affixed my signature in the presence of two witnesses.
50. 55. ELMER E. HAUER.
